CABINET FOR ELECTRONIC EQUIPMENT

Bertram W. Sathmary, Asbury Park, and Daniel Sinnott,
Wanamassa, N.J., and John Bruce, Wilton, Conn., as-
signors to Electronic Associates, Inc., West Long
Branch, N.J., a corporation of New Jersey

Filed Jan. 4, 1965, Ser. No. 83,258

Term of patent 14 years

(Cl. D26—5)

FIG. 1

FIG. 2

FIG. 3

FIG. 1 is a front perspective view of a cabinet for electronic equipment, showing our new design;

FIG. 2 is a right hand side thereof; and

FIG. 3 is a perspective view of the rear and left hand side thereof.

We claim:

The ornamental design for a cabinet for electronic equipment, substantially as shown.
